(57) **CLAIM**

We claim the ornamental design for a shirt with eyewear retaining system, as shown and described.

DESCRIPTION

FIG. 1 is a perspective view of a shirt with eyewear retaining system according to the claimed design; and
FIG. 2 is a front view of the shirt with eyewear retaining system according to the claimed design.

FIG. 3 is a back view of the shirt with eyewear retaining system according to the claimed design.

FIG. 4 is a right perspective view of the shirt with eyewear retaining system according to the claimed design.

FIG. 5 is a left perspective view of the shirt with eyewear retaining system according to the claimed design.

FIG. 6 is a top view of the shirt with eyewear retaining system according to the claimed design; and,

FIG. 7 is a bottom view of the shirt with eyewear retaining system according to the claimed design.

The ornamental design which is claimed is shown in solid lines in the drawings. The wavy lines shown in FIG. 1-6 illustrate contours in the fabric of the shirt with eyewear retaining system.

1 Claim, 6 Drawing Sheets
